ELASTIC FLUID TURBINE ASSEMBLAGE

Filed Aug. 26, 1929

Inventor:
John H. Doran,
by Charles V. Tullor
His Attorney.

UNITED STATES PATENT OFFICE

JOHN H. DORAN, OF SCHENECTADY, NEW YORK, ASSIGNOR TO GENERAL ELECTRIC COMPANY, A CORPORATION OF NEW YORK

ELASTIC-FLUID-TURBINE ASSEMBLAGE

Application filed August 26, 1929. Serial No. 388,459.

In the effort to save valuable floor space in central power stations, and especially in those stations located within the limits of large cities, where the turbo-generators are of large output, it has been proposed to divide the unit into two principal parts and to mount the high pressure part or unit and its electrical generator above the low pressure part or unit and its generator.

10 Such an assemblage, while it seems simple, in reality involves serious problems due to the fact that the parts expand and contract unequally, and to the further fact that it is not possible to prevent such changes but each 15 part must be permitted to follow its own law in this particular. A particularly difficult problem is to so arrange the turbines and their generators, especially the high pressure, high 20 temperature unit, that the vertical expansion of it and its supporting parts will not adversely affect the axial alignment.

My invention has for its object to provide in such an assemblage an arrangement of parts which will reduce to a minimum the 25 effects of unequal temperature changes of the turbine units and generators on the alignment of the shafts connecting them.

For a consideration of what I believe to be novel and my invention, attention is directed 30 to the accompanying description and the claims appended thereto.

In the drawing which is illustrative of my invention, Fig. 1 is a view in side elevation of an installation comprising high and low pressure 35 turbine units, each driving an electric generator, and Fig. 2 is an end view of the same.

3 indicates a low pressure turbine unit which is of the divided flow type, the steam 40 from the high pressure unit entering at 4 and flowing left and right to the exhaust conduits 5 and 6, which are connected to the condenser. 7 indicates the horizontal shaft of the turbine unit and 8 the casing of the generator, the 45 rotor of which is driven by the shaft.

10 indicates a horizontal high pressure turbine unit to which steam or other high temperature elastic fluid is admitted by the conduit 11. 12 indicates the exhaust conduit 50 which is connected to the inlet 4 of the low

pressure unit, the pipe for this being omitted in the interest of simplicity.

The high pressure turbine unit is supported above the low pressure unit and in order that the expansion of the metal in one shall have a minimum effect on the other, an arched member 13 is provided which bridges or extends cross-wise of the low pressure unit and which may be made in one or two pieces. This will depend largely upon the size of the units. 55 When large it will be usually found desirable to make the arched member in two parts as in the present instances, to facilitate casting and machining. Whether made in one or two parts, it is mounted on the casing of the low pressure unit, and preferably at as low a point as possible. The member should be made strong enough to sustain its load without appreciable change of shape. It is securely bolted in place at the flange along its lower 60 edge. The under surface of the member is separated from the casing of the low pressure turbine by a suitable space through which air may be circulated for cooling purposes. Where the load on the member is very heavy 65 it will be desirable to reinforce it on the under side by suitable cross ribs to prevent its tendency to spread. This member will expand and contract in a vertical plane as well 70 as in other directions with changes of temperature.

Mounted on the arched member is a pillow block 14 which carries one of the bearings for the shaft of the high pressure unit. The casing 15 of the unit is provided with a pair 85 of arms 16, one on each side, which are seated in openings in the pillow block and which support the unit at its inlet end. Each arm is connected to the block by a cross-key 17 which permits the casing and its arms to expand and contract without restraint. The pillow block is mounted to slide longitudinally in gibs 18, Fig. 2, and such sliding movement is effected by the expansion of the turbine casing.

As the arched member and turbine casing heat, they expand in a vertical plane as well as in other directions, and this vertical expansion naturally raises the shaft by a certain amount which, though small, is of seri-

ous moment unless suitably compensated for. The generators 19 and 19' expand less than the turbine units, and especially so under changes in load. The net effect is to raise the 5 shaft of the high pressure turbine unit more than the shaft of its generator is raised. A coupling 20 of any suitable construction is located between the adjacent ends of the two shafts and is intended to and does compensate for some lack of alignment. However, if the amount of misalignment is large it may cramp the coupling and cause excessive wear and also other and more serious damage. A 10 similar coupling is provided for the low pressure turbine and its generator. To reduce the effects of the unequal expansion and contraction of the parts mentioned above, a support is provided which averages the expansions of the arched member and hot end of 15 the turbine with that of the generator, and upon this support the pillow block and exhaust end of the turbine are mounted, and upon which they are anchored by the cross-key 21, which preserves the initial setting 20 while permitting the inlet or hot end of the turbine to slide in gibs 18. The support comprises a pair of parallel beams 22 and 23, which extend longitudinally of the turbines and are rigidly fastened to the arched member 25 at one end and have a sliding connection with the generator casing 19 at the other, as by means of top and bottom brackets 24, there being a suitable end clearance for the beams as indicated at 25. The beams 30 are connected by a third or cross-beam 26, which stiffens the structure and which, with the side beams, supports the turbine at its exhaust end and its pillow block 27, the latter being located approximately half way 35 between the arched member and the generator casing and held by the cross-key 21 and a longitudinal key in the vertical plane of the shaft. The generator shaft has a bearing 28 which is supported by the generator 40 casing. By this arrangement the coupling 20, instead of being subjected on the turbine side to the full effects of the vertical expansion and contraction of the arched member and associated parts, and on the generator side to the vertical expansion and contraction 45 of the generator casing, is subjected to only a fraction of the total difference, the exact amount depending upon the location of the pillow block 27 and parts which support the 50 turbine casing with respect to the two opposite ends of the beam support 22-23. By properly positioning the parts and their relation one to the other in the manner shown, the effects of the unequal expansion on the 55 coupling can be reduced to a negligible amount.

The beams 22-23 form a bridge between the arched cross-member 13 and the casing of the generator and because of their shape and position may be made as strong as is neces-

sary. The beams are also free to slide on the generator brackets 24 as they expand and contract. Being spaced above the right hand part of the casing of the low pressure unit they may be cooled in any suitable way, if 70 desired.

What I claim as new and desire to secure by Letters Patent of the United States is:

1. In a turbine installation, the combination of a low pressure turbine unit, a high pressure turbine unit, an apparatus driven by each unit, a coupling which unites the shaft of the high pressure unit with that of its driven apparatus, a supporting member for one end of the high pressure unit which is carried by the casing of the low pressure unit and is in spaced relation thereto, and a longitudinally extending means which supports the other end of the high pressure unit, is secured to the member at one end and is 80 slidably supported by said driven apparatus at the other end.

2. In a turbine installation, the combination of a low pressure turbine unit, a high pressure turbine unit, an apparatus driven thereby, a coupling which unites the shaft of the high pressure unit with that of the apparatus, an arched member which bridges the low pressure unit, is supported by its casing, and supports the inlet end of the high pressure unit, and a pair of longitudinally extending beams which support the exhaust end of the high pressure unit, are secured to the arched member at one end and are mounted to slide longitudinally on the said apparatus at the other end.

3. In a turbo-generator installation, the combination of high and low pressure turbine units, the former being mounted above the latter, a generator driven by each of said units, the generators being arranged one above the other, said units and generators expanding unequally under working conditions, a member which extends cross-wise of the low pressure unit, is carried by the casing thereof and supports one end of the high pressure unit, a longitudinally extending support for the other end of said high pressure unit, which is supported at one end by the member and at the other end by the casing of a generator.

4. In a turbine installation, the combination of high and low pressure turbine units arranged one above the other, an apparatus driven by each of the units which are also arranged one above the other, an arched member which extends cross-wise of the low pressure unit, rests at its lower ends on the casing thereof, and supports one end of the high pressure unit, spaced longitudinal beams which support the other end of the high pressure unit, are fastened to the arched member at one end and are mounted to slide longitudinally on the casings of the apparatus driven by said units at the other end.

5. In a turbine installation, the combination of a low pressure turbine unit, an apparatus driven thereby, an arched member which bridges the casing of said unit, a high
5 pressure unit located above the low pressure unit which is slidingly supported at one end on the member, an apparatus driven by the high pressure unit which is located above that driven by the other unit, beams which
10 are fastened to the member at one end, means carried by the apparatus upon which the other ends of the beams are free to slide due to temperature changes, and means carried by the beams at a point intermediate between
15 their ends for holding one end of the casing of the high pressure unit in fixed position while permitting the other end to slide on the member.

In witness whereof, I have hereunto set my
20 hand this 23rd day of August, 1929.

JOHN H. DORAN.
